UNITED STATES PATENT OFFICE.

CHARLES METTAM, OF NEW YORK, N. Y.

CONSTRUCTION OF IRON HOUSES.

Specification of Letters Patent No. 11,290, dated July 11, 1854.

To all whom it may concern:

Be it known that I, CHARLES METTAM, of the city, county, and State of New York, have invented a new and useful Improvement in the Construction of Iron Houses; and I do hereby declare that the following is a full, clear, and exact description of the same, reference being had to the accompanying drawings, forming part of this specification, in which—

Figure 1, is a front elevation of a portion of a building constructed according to my invention. Fig. 2, is a transverse vertical section of the same. Fig. 3, is a plan.

15 Similar letters of reference indicate corresponding parts in the several figures.

This invention consists in erecting the columns of the upper stories upon chairs, which can be adjusted easily to any desirable 20 position on the breast summers, and which when placed directly over the columns of the story below, to support columns immediately above them, serve to connect the breast summers, in such a way as to provide 25 for their longitudinal expansion and contraction.

To enable those skilled in the art to make and use my invention, I will proceed to describe its construction and operation.

30 A, A, A, represent the columns of the front of a lower story of a building; and B, B, the breast summers resting upon the columns in the usual way.

C, C, are the chairs upon which the upper 35 columns, A', A', A', are erected, which consist each of a broad flat plate, as large, or larger than the base of the column, with a perpendicular piece, a, of such form as to fit to the interior of the column, and another 40 perpendicular piece, b, fitting to the front

or other part of the exterior of the column. The pieces, a, and b prevent the column moving upon the chair. The chairs are placed upon any part of the breast summers that may be desirable, and are secured 45 thereto by bolts and nuts, c, c, for which slots d, d, are provided in the chairs, so that the chairs may be adjusted sidewise, and so that when a chair rests upon the ends of the two breast summers—as it will when the 50 columns of the upper tier are to be placed over the lower ones—the longitudinal expansion, or contraction, of the summers may be allowed. Before proceeding to erect the columns, A', A', A', the chairs should 55 severally be adjusted to the required condition, and may be secured before their respective columns are erected.

This method of erecting the columns upon chairs, saves much labor, as the chairs may 60 be adjusted exactly in the required positions before the several columns are raised, and the columns may be set up in their place at once without any adjustment. Much labor is thus saved, as the adjustment 65 which is necessary to bring a heavy column to a desired position is dispensed with, and the adjustment of a comparatively light chair only rendered necessary.

What I claim as my invention, and desire 70 to secure by Letters Patent, is:—

The combination of the chairs, C, C, C, with the breast summers, B, B, B, and the columns, A, A, A, substantially in the manner herein set forth.

CHAS. METTAM.
